UNITED STATES PATENT OFFICE.

JOHN F. MOORE, OF CENTRALIA, WISCONSIN.

SPRING FOR WAGON-SEATS.

SPECIFICATION forming part of Letters Patent No. 376,718, dated January 17, 1888.

Application filed July 9, 1886. Serial No. 207,615. (No model.)

To all whom it may concern:

Be it known that I, JOHN F. MOORE, a citizen of the United States of America, residing at Centralia, in the county of Wood and State 5 of Wisconsin, have invented certain new and useful Improvements in Springs for Wagon-Seats, of which the following is a specification, reference being had therein to the accompanying drawings.

My invention is a spring-bearer, more especially adapted to the springs of wagon-seats, and embraces, in brief, the following novel features: a half-elliptic spring-body having an intermedial and counter-arched spring-seat 15 and a pair of counter-lugs upon the extremity of each spring-bearing arm, all of which and their purposes are hereinafter more fully described, and illustrated by the accompanying drawings, in which like letters designate identical parts of said invention in the different 20 figures, respectively.

Figure 1 is a side view of said device, showing said counter-arched spring-seat, the oppositely-curving shoulders of the bearing-arms, 25 and said securing pairs of counter-lugs at the extremities of the same. Fig. 2 is an under view of said device. Fig. 3 is another side view of said device, showing the wagon-seat spring-bolted into its counter-arched spring-seat, and the said pairs of counter-lugs at the 30 outer ends of said spring-bearing arms overlapping the top edge of the sectional portion of a wagon-body side; and Fig. 4 is a cross-section of one side of a wagon-body, and shows 35 an end view of said spring-bearer securely resting upon said body-side.

The letter A represents said spring-bearer, which is made preferably of malleable or drop-pressed spring metal and of the general shape 40 shown. The springy arms d rise toward their curved shoulders b sufficiently to prevent the gravity of any superincumbent body on the wagon-seat to press said bearer-spring down upon the top edge of the wagon-body B, and are 45 provided with the counter-arching spring-seat c, into which the wagon-seat spring C is firmly bolted, as shown. At the extremity of each

said arm of the bearing-spring are formed a duplicate pair of rigidly and downwardly projecting counter-lugs, d, which are made to freely 50 overlap the top edges of the opposite vertical sides of the wagon-body, as shown, and thereby secure the wagon-seat safely in place, and at the same time allow for the proper extension and retraction of said bearing-spring ends, 55 while counter-springing to the motion of the moving wagon and its loaded seat-spring; hence said device affords a safe and doubly-springy seat upon the wagon and an extremely compensative and protective elasticity to the 50 resiliency of the wagon-seat spring, especially if said seat is occupied by very heavy weights riding over a very rough road. Said device also forms a very readily and economically 65 made and useful article of manufacture. 65

I am aware, from the state of the art in relation to wagon-seat springs, that said vehicle-springs have more or less immediate support and security from the adjustably hooking or riding "brackets" or "risers" to which they 70 are bolted or by which they are rigidly clamped; but I am not aware, neither does the history of said art disclose, that any of said risers or brackets exhibit any elastic or springy quality, 75 or were ever intended to subserve such quality, or were ever made of any such material as ever did or could produce the results of an extremely compensative and protective spring-seat for a wagon-seat spring.

Therefore, what I claim as new, and desire to 80 secure by Letters Patent, is—

The bearer of a wagon-seat spring, consisting of a semi-elliptical spring-body having the counter-arched spring-seat, elastic arms, and the duplicate pairs of counter-facing, overlapping, and compensatively-sliding arm-lugs, 85 substantially as and for the purposes herein specified.

In testimony whereof I affix my signature in presence of two witnesses.

JOHN F. MOORE.
